UNITED STATES PATENT OFFICE.

PAUL J. SCHELLER, OF EVANSVILLE, INDIANA, ASSIGNOR TO THE SLIDE-O-GRAF COMPANY, OF EVANSVILLE, INDIANA, A CORPORATION OF INDIANA.

MOTOR-OPERATED CARD AND PICTURE DISPLAY APPARATUS.

1,208,218.

Specification of Letters Patent. Patented Dec. 12, 1916.

Application filed December 18, 1915. Serial No. 67,664.

To all whom it may concern:

Be it known that I, PAUL J. SCHELLER, a citizen of the United States, residing at Evansville, county of Vanderburg, and State 5 of Indiana, have invented certain new and useful Improvements in Motor-Operated Card and Picture Display Apparatus, of which the following is a specification.

This invention relates to motor-operated 10 card and picture display apparatus.

The object of the present invention is to provide improvements on the electric motor-operated card and picture display apparatus of my application, Serial No. 18,013, 15 filed March 30, 1915, to the end that the construction will be simplified, improved, greater regularity of the step-by-step movement of the chain of slide carriers will be obtained and all wobbling or shaking there- 20 of obviated, thus insuring greater perfection in the display of the pictures carried by the slide.

With the foregoing ends in view, the invention consists, first, of an improved com- 25 bined reflector and guide adapted to coöperate with the idle stretch of the chain of slide carriers to prevent it from wobbling or shaking and also to serve as a reflector for the illuminating device used to project 30 the pictures on the other stretch of the chain of slide carriers; second, in an improved construction of chain and slide carriers, whereby the chain or carrier is rendered light, easily flexed when passing around the 35 drums or wheels, and made adaptable to being guided and to conform to the drums as well as permitting the easy insertion and removal of the slides and the proper tension thereof; third, in an improved form of drum 40 or reel.

The embodiments of the invention which are set forth hereinafter and shown in the accompanying drawings are to be considered as illustrative, rather than restrictive, 45 of the scope of the invention inasmuch as my improvements are susceptible of modification.

In the accompanying drawings, Figure 1 is a front perspective; Fig. 2, a rear eleva- 50 tion with the door open; Fig. 3, a vertical section through the case, the operative parts being in full and in dotted lines; Fig. 4, a detail of a portion of the slide carrier; Fig.

5, a cross section on line 5—5, Fig. 4; Fig. 6, a cross section through one of the drums; 55 Fig. 7, a detail face view of one of the links of the slide carrier; Fig. 8, a side view thereof; Fig. 9, a detail of a modification by which the lower drum may be dispensed with; and Fig. 10, a detail of another modification showing rollers which may be substituted for the guide for the rear stretch of the slide carriers.

The apparatus is preferably contained within a cabinet or box-like structure 1 65 which has a platform 2 intermediate its upper and lower ends for the support above or below said platform of the motor 3 and the operating means 4, the latter being sub- 70 stantially the same as set forth in my application Serial No. 18,013, and operating in the same manner except that it is arranged to drive the shaft 5 of the upper reel or drum 6 instead of the shaft 7 of the lower drum or reel 8, and the ratchet wheel 9 on 75 the shaft 5 has eight teeth instead of six, as the drums 6 and 8 are octagonal instead of hexagonal, as in my said application. As the motor 3 and driving means 4 constitute no part of the present invention, it is un- 80 necessary to give a detailed explanation thereof. The electric motor 3 imparts a rocking movement to the lever 4^a, which causes the pawl 4^b to turn the ratchet wheel 9 step by step, allowing a suitable pause or 85 dwell of the picture in between the turnings of the ratchet wheel 9 so that the pictures remain projected or displayed for a sufficient time for them to be observed.

The reels or drums 6 and 8 are shown in 90 Fig. 6. These drums are preferably of sheet metal having sides or heads 10 provided with slightly outstanding flange sections 11 corresponding in number to the eight sides 12 of the drum. The parts 11 may be in- 95 tegral with the heads 10 or eight separate pieces secured or riveted thereto. The body of the drum may be of sheet metal and secured to the ends 10 in any suitable manner.

The slide carrier has two chains 13 and 100 14 composed of jointed, flat links, as shown in Figs. 4, 5, 7 and 8. Each link 15 is provided at one end with a central hinge member 16 and at the other end with two hinge members 17. Short rivets 18 constitute the 105 pivots for the hinge members 16 of one link

and the members 17 of another link. The links are of a length adapting them to properly fit the sides 12 of the drums so that the pivots 18 will lie at the angles where 5 the sides of the drum meet.

The slide holders 19 constitute the cross connection between the chains 13 and 14. Each slide holder is of open and rectangular form, being provided with overhanging 10 lips 20 at its top and bottom and flanges 21 at its sides. The slide holders are riveted to the links 15 of the chains 13 and 14, as at 22. The slides 23 can be readily slipped over the flange 21 and under the lips 20 and 15 thereupon the lips and the flanges 21 will retain them, subject to ready removal for the substitution of others when desired.

The front stretch of the chain of slide carriers passes through the exposure or 20 slide-receiving box or house 24, from which projects a telescopic focusing tube 25 containing the lenses for the projection of the picture.

The light, such as a small electric arc or 25 incandescent light 26 is suitably arranged back of the slide-receiving box or house 24 for the purpose of illuminating and projecting the picture slide which is in the box or house 24. To serve as a reflector for the 30 light and also as a guide for the rear stretch of the chain of slide carriers, I provide a vertically arranged elongated plate 27 which, on its face 28 nearest the light 26, may be highly polished, colored white, silvered, or 35 otherwise adapted to serve as a reflecting back-ground for the light 26 and also to completely obscure the series of slides constituting the back stretch of the chain so that the full effect of the rays from the 40 light 26 will be had on the slide which is in the box 24 and thus clearness of projection is obtained. On its rear face, the plate 27 may be provided with a pair of vertically arranged guide flanges 29 and 30 adapted 45 to easily, yet snugly, engage the chains 13 and 14 and guide the rear stretch of the slide carrier as it moves along, step by step, and thus prevent any shaking, wabbling or displacement thereof which would interfere 50 with the accurate and regular advance of the chain of slides and the projection of the slides, one at a time.

In card and picture exhibitors of the step-by-step, motor-operated type, there is considerable shaking and vibration due to the 55 operation of the mechanical movement which brings about the step-by-step advance and arrest of the chain of slide carriers. My combined reflector and guide minimizes 60 shaking, wabbling, or displacement of the chain of slide carriers, due to this cause.

In Fig. 9, I have shown a detail of a 65 modification of the slide-receiving box or house 24 wherein a roller 31 extends cross-wise in said box and bears against the chain

of slide carriers and holds the slide carrier in the box against the rear wall thereof and also prevents swaying or wabbling of the front stretch of the chain of slide carriers. When the roller 31 is employed, the drum 8 70 may be dispensed with, if desired, and the lower portion of the chain of slide carriers will then simply hang free. If preferred, the drum 8 can be used when the roller 31 is provided. 75

In Fig. 10, I have shown a modification by which the guide plate 27 and its flanges 29 and 30 may be dispensed with and for the purpose of holding the rear stretch of the chain of slide carriers from shaking or 80 wabbling, there will be provided rods 32 fixed to the sides of the case 1 and provided with flanges 33. Loosely mounted on the rods are rollers 34 which are limited 85 in their longitudinal movement by the flanges 33 and bear against the rear stretch of the chain of slide carriers.

Having thus described my invention, what I claim as new and desire to secure by Letters Patent, is:—

1. In a slide exhibiting apparatus, the combination with a chain of slide holders, of a projecting device before which the chain of slide holders is adapted to pass, a source of light for the projection of the pictures, 95 and a combined reflector and guide serving as a reflector for the source of light and a guiding device for the chain of slide holders.

2. In a slide exhibiting apparatus, the combination with an endless chain of slide 100 holders, of a projecting device before which one stretch of the chain of slide holders is adapted to pass, a source of light for the projection of the pictures, and a combined reflector and guide serving as a reflecting 105 back-ground for said source of light and as a guide for the remaining stretch of slide holders.

3. In a slide exhibiting apparatus, the combination with an endless chain of slide 110 holders, of a projecting device before which one stretch of the chain of slide holders is adapted to pass, a source of light for the projection of the pictures, a reflecting plate disposed at the back of the source of light 115 and serving as a reflector therefor, and provided with flanges between which the remaining stretch of the chain of slide holders is adapted to pass, said slide holders being adapted to pass over the face of said plate. 120

4. In a slide exhibiting apparatus, the combination with upper and lower reels or drums, of an endless chain of slide holders adapted to run over said reels or drums, a projecting device for displaying the matter 125 carried by the slide holders and having means for guiding the front stretch of said endless chain of slide holders, and guiding means, independent of said drums, adapted to directly coöperate with, and guide, the 130

central portion of the rear stretch of said chain of slide holders rearwardly of the projecting and guiding device aforesaid.

5. In a slide exhibiting apparatus, a slide carrier comprising articulated flat links arranged in pairs and independent slide holders secured to the respective pairs of links and constituting bridging and bracing means for them.
- 10 6. In a slide exhibiting apparatus, a slide carrier comprising articulated flat links and slide holders secured thereto and constituting bridging and bracing means for the respective pairs of links, said slide holders

having lips to engage the slides, and retaining means for the slides.

7. In a slide exhibiting apparatus, a slide carrier comprising articulated flat links and slide holders secured thereto and constituting bridging and bracing means for the respective pairs of links, said slide holders being of open rectangular form and having over-hanging lips on two of their sides and retaining flanges on the other sides.

In testimony whereof, I hereunto affix my signature.

PAUL J. SCHELLER.
